UNITED STATES PATENT OFFICE.

ERNEST S. JAROS, OF COLUMBUS, OHIO, ASSIGNOR TO THE UNITED DEMONSTRATING MACHINE COMPANY, OF COLUMBUS, OHIO, A CORPORATION OF OHIO.

ADVERTISING DEVICE.

1,239,014.

Specification of Letters Patent.

Patented Sept. 4, 1917.

Application filed November 6, 1912. Serial No. 729,856.

To all whom it may concern:

Be it known that I, ERNEST S. JAROS, a citizen of the United States, residing at Columbus, in the county of Franklin and State of Ohio, have invented certain new and useful Improvements in Advertising Devices, of which the following is a specification.

My invention relates to advertising devices and is particularly directed to the provision of means for demonstrating the wearing qualities of clothes in a form that has hitherto never been approached. More specifically, my invention aims to provide means for demonstrating the elasticity of textile or other materials and also for demonstrating the soundness of all points of connections such as seams, etc. As a means of illustration, I have shown this principle applied to a glove testing machine and it is my object to apply the above tests to the various portions of this glove that are most liable to become worn, or to tear in actual wear.

A further aim is to attract attention to the wearing qualities of the articles on display by providing means for indicating the intensity of the applied forces used in the demonstrating operation. I believe it to be a material advance in the art to allow the observing public to acquaint themselves with the severe tests applied to these garments and as a means for attaining this result, I have provided a plurality of scales registering in units of pull, preferably, pounds. In order to demonstrate the longevity of the articles on display under varying conditions, I have provided means for applying wearing actions of varying intensities and also indicate these varying intensities by means of a plurality of scales.

A further object of my invention is to so construct the operating mechanism that it may at all times be within the vision of the observing public through a display opening arranged in any desired place in the housing structure. In the present instance, I have shown the front of the cabinet as being equipped with plate glass and thereby allowing a clear view of the internal operating mechanism. This feature is of importance in that the public at large is ever ready to believe that deception has been practised in the various demonstrations of wearing ap-

parel and that a view showing clearly the internal operating mechanism, any existing doubt should be removed.

The preferred embodiment of my invention is shown in the accompanying drawings, in which similar characters of reference designate corresponding parts, and in which:

Fig. 1 is a front elevation of my advertising device shown in position of operation,

Fig. 2 is a sectional plan taken on line 2—2 of Fig. 1 and looking in the direction of the arrow,

Fig. 3 is a detail in perspective of a portion of the operating mechanism,

Fig. 4 is a detail in perspective of another portion of the operating mechanism,

Fig. 5 is a side elevation of my advertising device in assembled condition within a cabinet, and,

Fig. 6 is a rear view of the same with a portion of the super-structure broken away.

In the drawings, I have shown a cabinet 1 having an upper cross bar 2 beneath which are suspended a plurality of scales 3, 4 and 5 held against oscillation by a rod 6 connected to their rear faces. The lower ends of the draw-beams 7 of the scales are preferably provided with rings 8 to which are fastened gripping elements 9 operated to open or closed position by butterfly nuts 10. The article to be demonstrated is securely fastened to these gripping elements in any desired position and at points opposite such attachment are complementary gripping elements 11 of similar construction and carrying rings 12 at their lower ends.

Carried within the casing 1, and resting upon the floor thereof, is a motor 13 having its armature shaft extended and provided with a worm 14. In working engagement with this worm is a worm wheel 15 carried upon a shaft 16, which shaft is supported between vertical standards 17 and which also carries a gear 18 at one end. Meshing with this gear 18 is a pinion 19 carried upon a shaft 20, which shaft is mounted in a position directly below the gripping elements 9 and 11 and is supported by upright standards 21. Thus it will be seen that rotation of the motor will cause rotation of the shaft 20 in a definite known ratio and in order to

apply a stretching action to the article upon display, I provide a plurality of disks 22 slotted as at 23 for the reception of a shoul- 5 dered eccentric pin 24 held in any adjusted position by tightening of the nut 25. To- 10 ward the rear of the cabinet, I have pro- 15 vided a plurality of standards 26 which piv- 20 otally carry forwardly extending lever arms 27, which lever arms are placed in a coöper- 25 ative position with respect to the eccentric pins 24. At the forward end of each lever arm 27 is an embracing element 30 pivotally mounted upon the pin 31 passing through the lever and having a threaded aperture in 30 its upper side for the reception of connecting 35 rod 32. Each connecting rod 32 is provided with an integral hook 33 at its upper end, which hook is adapted to engage the rings 12 carried by the gripping elements 11. 40 Should it be desired to at any time alter the effective length of any connecting rod 32, this may be done by screwing the same fur- 45 ther into the embracing element and may subsequently be locked in its adjusted po- 50 sition by the lock nut 33a.

From the description thus far given, assuming the articles to be displayed have been suitably supported by the gripping elements 9 and 11, rotation of the motor 13 will 55 transmit a rotary motion to the shaft 20 and consequently causes the eccentric pin 24 to travel in the path of a circle. The construction of the scales 3, 4 and 5 is such as to normally return to zero position and thereby 60 maintain the lever arm 27 in partially ele- 65 vated position. However, upon the approach of the eccentric pin 24, this lever arm is depressed, the amount of which depends upon the adjusted position of the eccentric pin in the slot 23. This downward move- 70 ment of the lever arm 27 causes a stretching action to be applied to the garment on display, the amount of which is clearly indicated by the pounds pressure shown by the 75 scales.

However, the lever arm 27 is of an ap- 80 preciable weight and naturally this weight will also be registered by the scales. To overcome this, I have provided a spring 34 85 suspended from the casing and terminating 90 at its lower end in the threaded extension 35. At a point approximately the center of the lever arm 27, I have shown an upwardly ex- 95 tends threaded rod 36 removably engaging 100 a ring 37 carried by the lever arm. The 105 threaded portions 35 and 36 are adjustably connected together by means of the turn- 110 buckle 38, which turnbuckle may be adjust- 115 ed to the desired position to indicate zero 120 weight upon the scales by the indicator arm. 125

The lower portion of the forward face of the cabinet is preferably provided with a plate glass or other transparent front 39, which front is supported in any desired man- 130 ner in the lower framework of the structure.

It will thus be apparent that the operating mechanism will at all times be open to inspection by the public and to further facilitate sureness of this inspection, I have provided incandescent lamps 40 supported by a portion of the rear structure of the cabinet and preferably hidden from view. By this means, the interior of the cabinet, carrying the operating mechanism, may at all times be properly illuminated.

I have shown my present device as applied in demonstrating gloves and have shown it as testing the seams of a finger, also the amount the palm portion will stretch and as testing the point of jointure of the thumb with the palm portion, these being usually conceded to be the portions to show wear. It will be apparent from the foregoing description, that the gloves thus carried suspended between the gripping elements 9 and 11 may be subjected to a very severe test and further, from the structure of the cabinet with its transparent front and the indicating scales, the public may at all times be the sole judge of the severity of these tests. 90 Various adjustments are also provided for varying the intensity of the applied forces and for compensating for the influences of the operating mechanism.

What I claim, is:

1. An advertising device comprising a plurality of scales, means for attaching an article of wearing apparel to each of said scales, said articles being attached in dissimilar positions, and means for automatically and successively subjecting each article of apparel to a stretching action, said means being such that the stretching actions increase in intensity from one of said articles to another.

2. An advertising device comprising a plurality of suspended scales, means for attaching an article of apparel to each of said scales, and means for automatically and successively subjecting each article of apparel to a stretching action.

3. An advertising device comprising a plurality of suspended scales, means for attaching an article of apparel to each of said scales, and means for automatically and successively subjecting each article of apparel to a stretching action, said last means being such that the stretching action of one article is completed before it is instituted for the succeeding article.

4. An advertising device comprising a plurality of suspended scales, means for attaching an article of apparel to each of said scales, means for automatically and successively subjecting each article of apparel to a stretching action, and means for relieving said scales of the weight of said operating means.

5. An advertising device comprising a casing, a plurality of suspended scales, means for attaching an article of apparel to each of

said scales, a lever pivoted at its rear end for each of said scales, second attaching means for each of said articles operatively connected to the other ends of said levers, and means for automatically and successively depressing said levers to subject said articles to a stretching action.

In testimony whereof I affix my signature in presence of two witnesses.

ERNEST S. JAROS.
